CLAIM

The ornamental design for an inflatable aircraft mattress, as shown and described.

DESCRIPTION

FIG. 1 is top perspective view of the inflatable aircraft mattress of my design.

FIG. 2 is a top view thereof.

FIG. 3 is a bottom view thereof.

FIG. 4 is a front view thereof.

FIG. 5 is a rear view thereof.

FIG. 6 is a right side view thereof; and,

FIG. 7 is a left side view thereof.

1 Claim, 4 Drawing Sheets(56)
